UNITED STATES PATENT OFFICE.

HAROLD WILLIAM EDEN, OF CHICAGO, ILLINOIS.

DESIGN FOR A WASHING-MACHINE OR SIMILAR DEVICE.

55,371.

Specification for Design.

Patented June 1, 1920.

Application filed January 12, 1920. Serial No. 351,060. Term of patent 14 years.

To all whom it may concern:

Be it known that I, HAROLD WILLIAM EDEN, a citizen of the United States, and residing in the city of Chicago, county of Cook, and State of Illinois, have invented a new, original, and ornamental Design for a Washing-Machine or Similar Device, of which the following is the specification, reference being had to the accompanying drawings, forming a part thereof.

In the drawings:

Fig. 2 is a side elevation thereof.

Fig. 3 is a front elevation of the washing machine, showing the wringer partly broken away.

I claim:

The ornamental design of a washing machine or similar device, substantially as shown.

HAROLD WILLIAM EDEN.
